UNITED STATES PATENT OFFICE.

THOMAS A. PEARCE, OF PHILADELPHIA, PENNSYLVANIA.

DESIGN FOR THE ORNAMENTATION OF KNITTED SHIRTS.

SPECIFICATION forming part of Design No. 19,266, dated August 13, 1889.

Application filed July 3, 1889. Serial No. 316,443. Term of patent 7 years.

To all whom it may concern:

Be it known that I, THOMAS A. PEARCE, a citizen of the United States, residing in the city and county of Philadelphia, State of Pennsylvania, have invented and produced a new and original Design for a Knitted Shirt, of which the following is a specification, reference being had to the accompanying drawing, forming part thereof.

5 The leading feature of my design for a knitted shirt is the surface ornamentation thereof, consisting of a checkered band with side stripes on the front thereof.

10

In the drawings, A designates a knitted shirt having on the front thereof a checkered band B and on each side of the latter parallel stripes C.

I claim—

The herein-described design for the ornamentation of the surface of a knitted shirt, consisting of a checkered band and stripes on the front thereof, as shown and described.

THOMAS A. PEARCE.
